UNITED STATES PATENT OFFICE.

LORENZ MUTHER, OF WEST NEWTON, MASSACHUSETTS.

DEVICE FOR SETTING EYELETS IN FLEXIBLE MATERIAL.

1,112,643.

Specification of Letters Patent.

Patented Oct. 6, 1914.

Application filed January 31, 1914. Serial No. 815,672.

To all whom it may concern:

Be it known that I, LORENZ MUTHER, a citizen of the United States, residing in West Newton, county of Middlesex, Commonwealth of Massachusetts, have invented certain new and useful Improvements in Devices for Setting Eyelets in Flexible Material, of which the following is a specification, reference being had to the drawings accompanying the same and forming a part thereof.

My invention relates to a device for setting eyelets or rivets in one or more of the layers of a plurality of layers of flexible material.

The objects of my invention are to provide a device for setting eyelets in one or more of the layers of a plurality of layers of flexible material so that the portion of the eyelet bent over by the setting device will come between two of the layers of material and so it will not show from the outside. This type of eyelet setting is what is termed "blind eyeleting."

In practice, I preferably use my eyelet setting device as a means to punch the hole and feed the material in which the eyelet is to be set.

As shown, my setting device may be used in the type of eyelet setting machines illustrated in United States Letters Patent to P. R. Glass, No. 686,928, granted November 19, 1901. My improved setting device may also be used to set eyelets in the type of machine illustrated in United States Letters Patent to P. R. Glass, No. 673,815, issued May 7, 1901, in which case my device serves to punch the hole and set the eyelet only.

The improved eyelet setting device herein shown is equally well adapted to be used in any type of eyelet setting machine where separate punching and feeding devices are employed. In such cases my device will be used only to set the eyelet.

In the drawings accompanying this specification and forming a part thereof, the mechanism of an eyelet setting machine has not been shown, as my improved setting device is formed so as to be used with any of the machines now in general use, and particularly machines of the P. R. Glass types hereinbefore referred to. The drawings accompanying this specification show my setting device when used with the anvil and positioning point of the before-mentioned Glass Patent No. 686,928, and illustrates

the anvil setting device in its several positions when punching the material, feeding it, positioning the eyelet, and setting it.

In the drawings—Figure 1 shows the setting device at the completion of the operation of punching the material, and the position of the anvil and positioning point with an eyelet in place ready to be presented to the work; Fig. 2 illustrates the position of my setting device, the anvil and positioning point when the setting device has partially fed the material forward to receive an eyelet; Fig. 3 shows the setting device, the anvil in position with an eyelet passed through the lower layer of material, the upper end of the eyelet being pressed against the lower side of the upper layer of material; Fig. 4 illustrates the position of the anvil and setting device, as well as the upper and lower layers of materials at the completion of the setting or riveting of the eyelet in the lower layer of material; Fig. 5 is a plan of a section of material showing the holes in the upper layer and the eyelets set in the lower layer, the eyelets being illustrated by dotted lines; Fig. 6 is a sectional elevation taken through Fig. 5 on line 6—6; Fig. 7 shows my improved eyelet setting device when formed as a hollow punch, as well as a setting device, with the setting shoulder concave; Fig. 8 shows my setting device when formed as a hollow punch with the setting shoulder convex; Fig. 9 shows two thicknesses of flexible material in section, an eyelet and the eyelet setting device, with the end of the setting device pushed into the end of the eyelet sufficient to support it slightly and split it so that the end of the eyelet will come under the uppermost layer of material and push it upwardly as indicated; Fig. 10 shows a sectional elevation of the two thicknesses of material with the end of the eyelet spread somewhat more than in Fig. 9, and with the upper layer of the material shoved upwardly on the setting shoulder.

In my improved setting device, 1 is the shank of the setting device, which shank may be so formed as to secure it to the hereinbefore mentioned Glass eyelet setting machines, or may be shaped to secure it in other types of eyelet setting machines; 2 is the punch and punch-block which in the Glass machine is provided with a slight projection 3 which serves to press the strips of material 4 and 5 upwardly upon the lower end of the

setting device; 6 is the anvil upon which the head of the eyelet 7 rests, and 8 is a positioning point designed to catch and position the eyelet properly upon the anvil 6 as it is fed 5 from the hopper.

In the operation of setting an eyelet in the material, the eyelet is pushed upwardly so that its barrel end passes outside the lower end of the eyelet setting device 1 as illustrated in Fig. 3. It will be noted in Fig. 7 that the portion 9 of the eyelet setting device is slightly tapering so that as the anvil 6 pushes the eyelet upwardly the upper end 10 of the eyelet is slightly spread by the tapering portion 9, which spread occurs after the 15 end of the eyelet has passed through the lowermost layer of material, as shown in Fig. 3. The slight spreading of the upper end of the eyelet spreads it away from the portion 9 so that it will bear underneath 20 the layer 5 of the material and press said layer upwardly and over the setting-shoulder 10, and thereafter said setting-shoulder 10 contacts with the end of the eyelet and 25 bends it progressively outwardly until it assumes the position shown at 11, Fig. 4, thus setting the eyelet in the layer 4 rather than having it pass through both layers of material.

30 The shoulder 10 is exaggerated in Figs. 7 and 8 for the purpose of better illustrating its form and curvature. In practice the shoulder is approximately one-half the width of the bent over portion of the eyelet 35 after it is set. In practice, however, these shoulders protrude but slightly beyond the upper end of the tapering portion 9, and may be formed either convex or concave, as shown in Figs. 8 and 7. The setting device 40 is preferably provided with the contracted portion 12 so as to permit the upper layer of material to pass readily over the projecting eyelet setting-shoulder 10 without unduly stretching it.

45 It will be readily understood that in cases where the lowermost layer of material 4 has been reinforced by permanently cementing a reinforcing strip upon its inner or upper surface, or otherwise securing the reinforcing strip to it, that the eyelet will pass 50 through the lowermost layer as well as the reinforcing strip which may have been attached to it and be set on the upper surface of the reinforcing strip so that the turned-

over or riveted portion will come between the 55 reinforcing strip and the lower surface of the upper layer 5.

I do not confine my invention to a setting device having a hole passing axially through it as shown, as my setting device may be 60 used only for the purpose of setting eyelets and not for punching, as for instance in machines where the eyelet setting and punching devices are separate; *i. e.*, where a device is used to punch the hole and feed the 65 material and a separate device used to set the eyelet. Likewise, the eyelet setting device may come upwardly from underneath the layers of material and the eyelet be fed downwardly, or the eyelet setting device may 70 be operated horizontally with the layers of material in a vertical position.

I do not wish to confine my invention to the exact form or the manner of using it as a punching, feeding and setting device, as 75 it may be used for a setting device only, and this without departing from the spirit of my invention.

What I claim is—

1. A device for setting eyelets in one of a 80 plurality of layers of a flexible material, said device comprising an anvil and a coöperating setting device having a projecting setting-shoulder and a contracted portion above the setting-shoulder. 85

2. An eyelet setting device consisting of means for setting eyelets in one of the outside layers of a plurality of layers of material, comprising a lower anvil, an eyelet positioning device and an upper setting device 90 having a slightly projected setting-shoulder and a contracted portion above the setting-shoulder.

3. The combination of a punching and eyelet setting device for setting eyelets in 95 one or more of the layers of a plurality of layers of material, comprising a punch and a setting device having a projecting setting-shoulder and a contracted portion above the setting-shoulder. 100

In testimony whereof, I have hereunto set my hand, in the presence of two subscribing witnesses, this the 30th day of January A. D. 1914.

LORENZ MUTHER.
